UNITED STATES PATENT OFFICE.

ABRAHAM KNOBEL, OF LOUISVILLE, KENTUCKY, ASSIGNOR TO ROGERS,
RIDGEWAY AND FAITH, OF LOUISVILLE, KENTUCKY, A COPARTNERSHIP.

ELECTRIC RAILROAD-GATE.

No. 822,958.

Specification of Letters Patent.

Patented June 12, 1906.

Application filed December 30, 1905. Serial No. 293,917.

To all whom it may concern:

Be it known that I, ABRAHAM KNOBEL, a citizen of the United States, residing at Louisville, in the county of Jefferson and State of Kentucky, have invented a new and useful Electric Railroad-Gate, of which the following is a specification.

This invention relates especially to railroad-way-crossing gates; and the objects of my improvement are simplicity of construction, comparative inexpensiveness of manufacture, safety, economy, and ease of operation. These objects I attain by means of the mechanism illustrated in the accompanying drawings, in which—

Figure 1 is a side elevation with a side of the casing and the near side of the gate removed; Fig. 2, an edge view with the near edge of the casing removed; Fig. 3, a side elevation showing the manner of gearing the two gates together; Fig. 4, a plan view with the top of the casing removed, and Fig. 5 a plan view of the switch.

Similar reference-numerals refer to similar parts throughout the several views of the drawings.

The casing 1, the longer gate 2, and the shorter gate 3 constitute the body of the invention. The gate 2 is mounted on a pivot-shaft 4, which passes transversely through the upper part of casing 1. The shorter or sidewalk gate 3 is mounted on studs 16 and 17 on the sides of casing 1. A gear-wheel 14 is mounted on shaft 4 on the outside on one side of the casing, and a corresponding gear-wheel of the same size and meshing with gear-wheel 14 is mounted on stud 16 and rigidly secured to gate 3.

It will be understood that as gate 2 is opened or closed shaft 4 and gear-wheel 14, rigidly mounted thereon, are rotated, and by means of gear-wheel 15 gate 3 is opened or closed simultaneously. Within casing 1 is the gearing for operating the gate. It is driven by the electromotor 18, which is placed upon a shelf 19 within the casing. The shaft 12 of the electromotor is extended, and its outer end works in a journal-box 11, secured to one side of casing 1. On shaft 12 is mounted or integral a worm 10, which meshes with a worm-wheel 8, which in turn is secured on a counter-shaft 9. A pinion 7 is also mounted on counter-shaft 9 and

meshes with a driving-gear 16, loosely mounted on pivot-shaft 4. A spring-clutch member 5 is rigidly mounted on pivot-shaft 4 and disposed in frictional contact with gear 6 and is adjustable by means of a set-screw 20.

The electromotor 18 is electrically connected with a battery or other source of power through a starting and current-reversing switch 18, which may be located in the watch-house or any suitable distant place. The electromotor is preferably of the series-wound type and preferably driven by a primary battery which may be placed in the watch-house.

The gate 2 is provided at its inner end with counterweights 13, so that it is perfectly balanced, and thus requires very little power to operate.

The switch 18 may be of any form usually used and need therefore not be minutely described. It is provided with a lever 24, a handle 22, and stops to limit the motion of the handle, as shown in Fig. 5.

The operation of the device will now be understood. If the gate is to be closed, lever 24 is pushed around by the operator to the proper stop, as indicated, which starts the motor in the direction to rotate shaft 4, so as to lower the free ends of the gates. If the gate is to be opened, lever 24 is pushed around to the opposite stop, as indicated, which causes the motor to run in the opposite direction and raises the free ends of the gates. When lever 24 is placed between the stops or on the neutral point, the motor-circuit is opened and the gate remains at rest. It will be seen that with this arrangement the operator in the watch-house has complete control of the gate. If he has started it toward the closed position and a vehicle should be passing, he may immediately reverse the motor and raise the gate or stop it and hold it stationary until the vehicle has passed. Any number of these gates may be operated simultaneously by connecting them with a single switch, or a switch may be provided for each gate or for each set of gates, as when there are gates disposed on opposite sides of a broad street and on both sides of the railroad-tracks. The details of arranging the electric connections will be readily planned by those skilled in the art pertaining to the device.

It will be understood that the operator need not be careful to stop the motor after the gate has reached the closed or horizontal position, because the pivoted leg 21 near the 5 end of the gate resting upon the surface of the street prevents the gate from moving farther. The gearing within the casing 1 will not be injured by the force of the motor after the gate has come to a standstill, be- 10 cause the friction-clutch 5 will slip on gear 6, allowing the friction member 5 to stand still. The same will occur when the gate has reached the perpendicular position, when the portion carrying the counterweights 13 will 15 strike a spring-buffer 23 and stop the gate from further movement. In this case also the friction-clutch will act to prevent de- struction or derangement of the gearing. The clutch member 5 may be adjusted against 20 gear 6, so as to produce sufficient force to operate the gates against wind or the accumulation of snow and ice or to provide for other exigencies.

Having thus described my invention, so

that any one skilled in the art pertaining 25 thereto may make and use it, I claim—

1. In an electric-driven road-gate, the combination of a casing, a pivot-shaft, a driving-gear loosely mounted on said pivot-shaft, a friction member mounted on said 30 pivot-shaft to be operated by said driving-gear, a counter-shaft, a pinion on said counter-shaft meshing with said driving-gear, a worm-gear on said counter-shaft, and a worm meshing with said worm-gear direct-connected 35 with a motor-shaft, substantially as specified.

2. In a road-gate, the combination of a pivoted gate, a pivot-shaft on which said gate is mounted, driving-gear loosely mounted on said pivot-shaft; and a friction member rigidly mounted on said pivot-shaft in frictional contact with said driving-gear. 40

ABRAHAM KNOBEL.
